UNITED STATES PATENT OFFICE.

ETHAN I. DODDS, OF AVALON, PENNSYLVANIA, ASSIGNOR TO PRESSED STEEL CAR COMPANY, OF PITTSBURG, PENNSYLVANIA, A CORPORATION OF NEW JERSEY.

CAR PART.

No. 811,206.

Specification of Letters Patent.

Patented Jan. 30, 1906.

Application filed February 23, 1904. Serial No. 194,641.

To all whom it may concern:

Be it known that I, ETHAN I. DODDS, of Avalon, Allegheny county, Pennsylvania, have invented a new and useful Improvement in Car Parts, of which the following is a full, clear, and exact description, reference being had to the accompanying drawings, forming part of this specification, in which—

Figure 1 shows in plan view a channel-beam which has been cut and pressed laterally for the purpose of producing a brake-beam in accordance with my invention. Fig. 2 is a side elevation thereof. Fig. 3 is a vertical section on the line III III of Fig. 2. Fig. 4 is a side elevation illustrating a modified construction in which the middle member has a flange deeper at the middle than at the end portions and the flanges are directed downwardly. Fig. 5 is a view similar to Fig. 4, showing a modification in which the flanges are directed upwardly. Fig. 6 is a vertical section on the line VI VI of Fig. 5. Figs. 7, 8 and 9 are plan views of modified constructions of the brake-beam with the top member removed for purposes of illustration, Fig. 7 being a plan view of Fig. 2, Fig. 8 a plan view of Fig. 4, and Fig. 9 a plan view of Fig. 5. Fig. 10 illustrates a modification in which the top and bottom members of the brake-beam are bent. Fig. 11 is a vertical section on the line XI XI of Fig. 10. Figs. 12, 13, and 14 are views similar to Fig. 10, illustrating modifications. Figs. 15, 16, and 17 are sections on the lines XV, XVI, and XVII of Figs. 12 to 14, respectively.

The purpose of my invention is to manufacture brake-beams, bolsters, and other parts of railway-cars from metal pieces with as little possible waste of metal and with great strength and rigidity of construction. The saving which I thus obtain is very considerable, since heretofore the waste incident to the cutting and shaping of the parts of cars has constituted a large item of cost.

My invention consists in forming a car part, which may be a brake-beam, bolster, or other part of a car, by cutting through the middle portion of a metal piece so as to form a middle member, then separating such middle member transversely away from the side members and compensating for the shortening of the metal piece, preferably by bending the outer members, produced by the cutting operation, either away from the middle mem-

ber or laterally toward each other, so as to accommodate them to the deflected position of the middle member.

On Sheet 1 of the drawings, which illustrates the manner of making a brake-beam in accordance with my invention, I show a flanged metal piece, which may be an I-beam or a channel-beam and is indicated by the dotted outline in Fig. 1, and I slit it longitudinally through the web by two parallel cuts b b. Then by means of suitable dies or other apparatus I bend the cut beam into the shape shown in Fig. 2, bending the middle portion c downwardly and the two side members d d toward each other, so as to compensate for the shortening of the section produced by the down-bending of the middle member c. I also flange the middle member c, as indicated in Fig. 3, preferably by the same dies and at the same operation as that in which it is bent downwardly. In Fig. 2 I show this flange as being of uniform depth from end to end of the middle member.

Fig. 3 illustrates in full lines the shape to which the article is brought by the operations above described and by dotted line shows the original position of the side members d d before the bending operation.

In Figs. 4 and 8 the brake-beam is constructed as above described, except that the middle member c is flanged with outwardly-directed flanges which are deeper at the middle than at the ends, and said member c therefore has the tapering form in plan view, as shown in Fig. 8. The construction shown in Figs. 5, 6, and 9 is the same as in Fig. 4, except that the flanges of the middle member are inwardly directed.

The brake-beam made as above described may be fitted with the usual irons and attachments.

In the figures shown in the second sheet of the drawings instead of bending the side members d d, here marked d' d', laterally toward each other I bend them upwardly and away from the middle member c for the purpose of compensating for the shortening of the metal consequent upon the bending of the member c. In Figs. 10 and 11 the brake-beam thus made is constituted of a channel-section slit longitudinally through the web, as shown in Fig. 1, the parts thus slit being bent in opposite directions, the middle member c' being flanged downwardly, and the

2 flanges being of uniform depth from end to end. In the construction shown in Figs. 12 and 13 the flanges of the member c' are deepest at the middle, and in the construction shown in Figs. 13 and 17 they are inwardly directed.

In Figs. 14 and 17 I show the brake-beam when made from an I-beam section. In Figs. 14 and 17 the middle member c' is flanged and the flanges directed outwardly.

I-beams may be substituted for channels in any of the constructions shown in the drawings, and the middle member of any of them may be flanged in either direction.

15 In the figures above described the shortening of the metal followed by the bending of the middle member is compensated by the corresponding bending of the side members, either in a direction toward each other or in a direction away from the middle member.

20 The foregoing description will show that my invention may be modified in many ways within the definition of the claims and that it may be adapted to the manufacture of 25 beams, transoms, bolsters, end sills, &c., of different types, since

What I claim is—

1. A car part composed of a flanged metal piece slit in the web with longitudinal slits to

afford a middle member and side members, 30 said middle member and side members being bent away from each other in a direction transverse to the web, and the middle member being flanged; substantially as described.

35 2. A car part composed of a flanged metal piece slit in the web with longitudinal slits to afford a middle member and side members, 40 said middle member and side members being bent away from each other in a direction transverse to the web, and the middle member being flanged with flanges deeper at the middle portion; substantially as described.

45 3. A car part composed of a flanged metal piece slit in the web with longitudinal slits to afford a middle member and side members, 50 said middle member and side members being bent away from each other in a direction transverse to the web, and the side members being bent toward each other in the same plane; substantially as described.

In testimony whereof I have hereunto set my hand February 20, 1904.

ETHAN I. DODDS.
